UNITED STATES PATENT OFFICE.

ARTHUR J. WELLS, OF SYRACUSE, NEW YORK.

INDEX.

SPECIFICATION forming part of Letters Patent No. 433,223, dated July 29, 1890.

Application filed June 22, 1889. Serial No. 315,243. (No model.)

To all whom it may concern:

Be it known that I, ARTHUR J. WELLS, of Syracuse, in the county of Onondaga, in the State of New York, have invented new and 5 useful Improvements in an Index, of which the following, taken in connection with the accompanying drawings, is a full, clear, and exact description.

My invention relates to an improved index 10 for diaries and other books, and has for its object the production of a simple and effective device whereby I greatly facilitate the operation of finding memoranda or events recorded on a particular day, or information 15 properly classified in said book; and to this end it consists, essentially, in dividing or indexing the pages or leaves of the books into a certain number of divisions or classes and then subdividing or sub-indexing one or more 20 of said divisions or classes.

In describing my invention, reference is had to the accompanying drawings, forming a part of this specification, in which like letters indicate corresponding parts in all the 25 views.

Figure 1 represents an isometric perspective of my improved book or diary, one division of the cover thereof being thrown back for the purpose of illustrating the index; and 30 Fig. 2 represents a perspective of one of the divisions of my diary, illustrating particularly the arrangement of the subdivisions.

A represents the book or diary, which may be of any suitable form, size, or construction 35 to suit any desired purpose. The leaves *a* are also of suitable size, form, and construction, and of a desired number. These leaves *a* are by the index *a'* divided into a number of classes or principal divisions *b*. The preferable manner of forming these divisions is 40 to arrange the index-faces *b'* in line, one below the other, so that when the book is in the position illustrated in Fig. 1 all of said divisions will show to the eye. By placing the finger upon any one of said index-surfaces the remaining leaves in front of said leaf may be 45 quickly turned back. These index-surfaces *b'* are shown as formed by cutting out the edges of the leaves in the form of a triangle; but it 50 will be understood that they might consist of pieces of paper or other material secured to

the edge of said leaves, so that when the book is in the position illustrated in Fig. 1 the top face or a portion thereof of each of said pieces of paper or other material will be 55 exposed to view.

In the illustrated example of my improved index I place the name or abbreviation of the months upon the index-points *b'*. One or more of the main divisions or classes *b* are 60 subdivided or sub-indexed into divisions *b'*, as clearly shown in the drawings. This sub-index *a'* may be formed in precisely the same manner as the main index *a'*. Upon the index-surfaces *b'* of the sub-index *a'* letters or 65 symbols may be used which will designate subdivisions or classes of the main divisions or classes of the index *a'*. In the illustrated example I have placed upon these latter index-surfaces letters to represent the days of 70 the month.

By reference to the drawings and the foregoing description it will be understood that by placing the finger upon the index-point of the particular month desired the same can 75 be readily turned to, and after the month has been obtained by placing the finger upon the particular day required the memoranda or event recorded upon said page will be quickly 80 and readily brought to view. This is a feature of great advantage, since frequently in diaries and memorandum-books it is desirable to turn to a memorandum or an event recorded upon a particular day and month. With books provided with an index of my improved 85 construction it will be evident that the desired information is quickly and readily obtained. It will also be understood that with but slight additional cost this index may be readily provided upon any desired form of 90 book, and by this means an article of manufacture is produced which possesses features of great advantage.

This index may be formed upon books other than diaries and memorandum-books, and it 95 will be understood that I do not limit myself to subdividing or sub-indexing every one of the divisions of my improved index, but only such ones as are desirable. Neither do I limit myself in regard to the symbol which shall 100 be placed upon the index-points of my improved index, since it will be evident that

these can be varied to suit the purposes of the book upon which the index is provided. It will also be understood that I do not limit myself to the arrangement of the figures denoting the days of the month, since instead of placing the illustrated number of days upon each leaf one leaf may be used to denote as much as is desired.

10 The operation of my invention will be readily perceived from the foregoing description and upon reference to the drawings, and it will be understood that the same may be somewhat varied from the illustrated form and construction.

15 Having thus fully described my invention, what I claim as new, and desire to secure by Letters Patent, is—

1. The herein-described diary or book, the same being provided with index-divisions 20 having characters thereon for indicating the months of the year, and with subdivisions

formed in the aforesaid index-divisions, and having thereon characters for indicating the day of the month, substantially as set forth.

2. The herein-described diary or book, the 25 same being provided with index-divisions at one extremity of its side edge, characters placed on said divisions for indicating the months of the year, subdivisions in said index-divisions at the other extremity of said 30 side edge, and characters upon said subdivisions for indicating the day of the month, substantially as specified.

In testimony whereof I have hereunto signed my name, in the presence of two attesting 35 witnesses, at Syracuse, in the county of Onondaga, in the State of New York, this 20th day of June, 1889.

ARTHUR J. WELLS.
